UNITED STATES PATENT OFFICE.

EUGENE DARNELL AND LOUIS G. CASSIDY, OF WICHITA, KANSAS.

COMBINATION LADDER.

Application filed April 17, 1922. Serial No. 553,707.

To all whom it may concern:

Be it known that we, EUGENE DARNELL and LOUIS G. CASSIDY, citizens of the United States, residing at Wichita, in the county of Sedgwick and State of Kansas, have invented certain new and useful Improvements in Combination Ladders, of which the following is a specification.

This invention relates to ladders and has for its object the provision of a ladder consisting of sections which may be so combined as to form a step ladder, a stair ladder, or an extension ladder, or may be separately used as short straight ladders. The invention also seeks to provide novel means whereby the sections of the ladder may be held against separation when adjusted in any combination, and also to provide means whereby they may be readily assembled in any desired combination. A further object of the invention is to provide a structure which will permit a limited pivotal movement of one section upon the other, and also to provide a construction which will permit one section to be nested within the other and also slidably adjusted with respect thereto so as to be brought into any desired relation therewith, and another object of the invention is to provide a ladder which will be strong and durable and inexpensive to produce. The several stated objects of the invention and other objects which will incidentally appear in the course of the following description are attained in such a device as is illustrated in the accompanying drawings, and the invention resides in certain novel features which will be hereinafter first fully described and then more particularly pointed out in the appended claims.

In the accompanying drawings—

Figure 1 is a perspective view of our improved ladder arranged for use as a step ladder;

Fig. 2 is a side elevation showing the device arranged for use as a stair ladder;

Fig. 3 is a front elevation of portions of the device showing the manner in which the sections are combined to form an extension ladder;

Fig. 4 is a section on the line 4—4 of Fig. 3;

Fig. 5 is an enlarged perspective view showing the manner in which the minor section is engaged with and held to the major section when the sections are arranged to form an extension ladder;

Fig. 6 is an enlarged perspective view showing one means of preventing separation of the sections when they are arranged to form a step ladder;

Fig. 7 is a similar view showing another embodiment of the invention;

Fig. 8 is a detail perspective view of the upper end of the minor section;

Fig. 9 is a detail view showing the manner in which the sections are held together when the device is arranged as a stair ladder;

Figs. 10 and 11 are detail perspective views of portions of the major section;

Fig. 12 is a detail sectional elevation showing another embodiment of the invention;

Figs. 13 and 14 are detail views of the means for securing the rungs of the minor section.

In carrying out our invention, we employ two ladder sections 1 and 2 which, for convenience, will be referred to as the major section and the minor section respectively. The major section comprises side bars, each of which is longitudinally split so as to present two front rails or bars 3 and a rear somewhat larger rail or bar 4 connected by brackets so as to be held in fixed triangular relation and present a truss-like structure which will be light but very strong and durable. In Fig. 10, the said members of the side bar are connected by a substantially U-shaped bracket 5 having its shoulder secured to the member 4 by a bolt or similar fastening 6 and provided at the ends of its side members with outturned lips or lugs 7 through which bolts or other fasteners 8 are inserted into the members 3; the said bolts or fasteners 8 also passing into or through the rung 9 so as to secure the rung in place. It may be further noted that we have illustrated the rung as set into mortises formed in the outer faces of the members 3, but the rung may be secured directly to the outer faces of the side bars without seating in mortises, if so desired.

In Fig. 11, we have shown a bracket 10 consisting of a trapezoidal plate having depending flanges 11 at its parallel edges, and these flanges are secured to the members 3 and 4 respectively, as shown. With either form of bracket, the members of the side bar are secured rigidly in their desired relation so that a rigid strong side bar will be produced. It will be noted upon reference to

Fig. 1 that the side bars are parallel through the greater portion of their length but flared somewhat toward their lower ends and the minor section 2 of the ladder may thus fit 5 between the side bars of the major section and be guided thereby when being slid into the desired relation.

The lower ends of the side bars of the major ladder section are beveled, as indicated 10 at 12, so that flat surfaces will be provided to permit the said section to rest upon a floor or other surface when the device is employed as a step ladder or as a stair ladder, these beveled surfaces 12 being located at 15 that side of the section opposite the side carrying the rungs 9. Upon the same side of the side bars as the rungs 9, we secure to the lower ends of said side bars anchor plates 13, the lower ends of which are slightly 20 sharpened, as indicated at 14, and project below the adjacent surfaces of the side bars. When the device is used as an extension ladder, as indicated in Fig. 4, the ends of the anchor plates 13 will engage in the ground 25 or surface upon which the ladder rests so that slipping of the ladder will be prevented.

In the form of the invention illustrated more particularly in Figs. 1 and 6, the major 30 ladder section is provided at its upper end with a rung 15 on its rear side approximately in the same plane as the uppermost rung 9 upon its front side and the minor ladder section is composed of side bars 16 35 adapted to slide between the said rungs 9 and 15 and constructed at their upper ends upon their opposite sides with notches 17 and 18, the notch 18 being disposed below the notch 17 so that, if the minor section be 40 engaged between the rungs 9 and 15 and then slightly turned, the notch 17 will be brought into engagement with the upper inner corner of the front rung 9 and the notch 18 will be brought into engagement with the 45 lower inner corner of the rung 15. The walls of the notches are disposed at right angles to each other and they may be reinforced by a metal wear plate 19 which may be extended over the upper extremity of the 50 respective side bar and along the front and rear edges of the same, as clearly shown in Fig. 6. The notches will firmly engage the 55 respective rungs so that, when the device is set up for use as a step ladder, as shown in Fig. 1, spreading of the ladder sections will be prevented. To guard against collapse of the sections when the device is in use as a step ladder, we provide upon each side bar of the major section, a latch 20 consisting of a bar or elongated plate pivoted at 60 its lower end upon the rear side of the member 4 by a bolt or similar device 21 and having its upper end notched, as indicated at 22, to engage the longitudinally extending 65 corner of the adjacent side bar of the minor

section, as will be readily understood upon reference to Fig. 6. The latch is also constructed with a forwardly projecting flange 23 which may be used as a handle to manipulate the latch and, when the latch is not brought into use, will extend across the space between the members 3 and 4 at the inner side of said members so that it may be easily reached by the workman. When the latch is not in use, the handle 23 will lie between the side bars of the respective ladder sections. The side bars of the minor section carry rungs 24 which extend between said side bars and are preferably secured in place by such means as are shown in Figs. 80 13 and 14. The rungs 24 are preferably circular in cross section and have tapered ends, as indicated at 25. Through openings provided therefor in the side bars 16 of the minor ladder section, we insert thimbles or 85 sleeves 26 which are provided with annular flanges 27 near their inner ends so as to limit the extent to which the sleeves or thimbles may be inserted outwardly through the side bars. Washers 28 may be employed, one fitting against the inner side of the side bar 16 between the same and the flange 27 and the other washer fitting against the outer side of the side bar around the outer projecting portion of the sleeve or thimble. 90 After the washers have been properly placed, the outer free end of the sleeve is upset, as indicated at 29, so that the thimble or sleeve will be firmly secured in the side bar of the ladder section. The end of the 100 rung is fitted in the inner end of the sleeve and indentations 30 are then formed in the sleeve in any desired number so as to firmly secure the rung therein and prevent its withdrawal. 105

It will, of course, be readily understood that the minor section is of less width than the major section and may readily fit between the side bars of the major section so that, when the device is not in use, the two sections may be easily nested and, when it is to be set up for use the minor section may be easily slid to the proper position. The side bars of the minor section are provided at points intermediate their ends with other notches similar in all respects to the notches 17 and 18 so that, if it be desired to use the device as a stair ladder, as shown in Fig. 2, the two sections may be readily coupled so that the minor section will present a shorter 115 weight-sustaining length than the major section and thereby permit the lower ends of the two sections to rest upon different steps or upon other supporting surfaces having different elevations, as will be readily understood upon reference to Fig. 2.

Immediately adjacent the inner faces of the side bars 16, we pivotally mount upon the lowermost rung 24 locking feet 31 which are connected immediately below said rung 130

by a cross bar 32 whereby the locking feet are held in their proper relation, and this cross bar furnishes a convenient handle whereby the feet may be manipulated when 5 setting up the device as an extension ladder. The locking feet 31 are adapted to rest upon a rung 9 of the major section and are provided at their lower ends upon their opposite sides with stop plates 33 and 34, the 10 lower ends of which depend below the respective feet, as clearly shown in Fig. 4. A spring 35 is arranged between each locking foot 31 and the respectively adjacent side bar 16 and, in Figs. 3 and 4, this spring 15 is illustrated as a resilient wire bow having its opposite ends secured respectively to a locking foot and a side bar, the force of the spring being constantly exerted to maintain the locking foot in alinement with the 20 side bar. A bracket or lug 36 is also provided upon the side bar 16 below each locking foot 31 and between the plates 33 and 34. When the device is to be used as an extension ladder, the minor section is projected upwardly between the rungs 9 and 25 15 to the proper degree and the locking feet are then swung rearwardly so that the plates 33 will clear the immediately adjacent rung 9. The minor section is then 30 lowered slightly while the locking feet are in this rearward position, whereupon the plate 33 will pass in rear of the rung 9, as clearly shown in Fig. 4, the bracket or lug 36 being disposed between the rung and the 35 plate 34. Movement of the locking feet relative to the ladder sections will then be pivotally prevented inasmuch as movement in one direction will be stopped by the engagement of the plate 34 against the lug 40 36 and in the other direction by the engagement of the plate 33 against the rung 9 and the two ladder sections will thus be positively held in the extended relation and the ladder may be used without fear of falling. Upon reference to Fig. 3, it will be 45 readily noted that the cross bar or handle 32 is so located that it will be very slightly below the rung 15 and will not interfere with a person ascending or descending the ladder. When the sections are to be separated, 50 the minor section is raised slightly so that the stop plate 33 may clear the rung 9, whereupon the spring 35 will at once expand and swing the locking feet forwardly, the forward movement being limited by the 55 said stop plates 33 impinging against the respective lugs or brackets 36. In Fig. 5, we have shown a leaf spring 37 which may be used instead of the bow spring 35. This leaf spring is secured at its upper end to the adjacent locking foot and has its free end playing in a notch 38 in a bracket or lug 39 secured to and projecting inwardly from the adjacent side bar 16. This arrangement permits the use of a stronger 60 spring but does not economize space to the same extent as the first described arrangement, but either form is within the scope of our invention and either form may be used as may be preferred. 70

In the embodiment of the invention thus far described, the side bars of the minor section are of rectangular cross section having their opposite faces parallel and the notches in said side bars extend across the entire thickness of the same. The side bars may, however, be constructed with longitudinal ribs 40 upon their outer sides and the notches may be formed through these ribs, as indicated at 41. Instead of employing 75 the rungs 15, we may provide metallic locking and supporting heads 42 at the upper ends of the side bars of the major section. These heads are castings adapted to be rigidly secured to the upper extremities of the side bars and are provided upon their inner faces with flanges to guide the minor section in its movements and also effect locking engagement with the longitudinal ribs 80 40. One flange 43 is disposed at the under or rear side of the major section and extends parallel, through its lower portion, with the edge of the major section, but the upper portion of this flange is projected outwardly to present a socket or notch 44, the walls of 85 which are disposed substantially at a right angle to each other and are adapted to receive the upper extremity of the rib or flange 40. Spaced inwardly from the flange 43 are upper and lower flanges or ribs 45 and 46, the lower flange 46 being of arcuate formation and depending below the lower edge of the main portion of the casting or head. The upper flange 45 has its upper extremity 47 disposed parallel with the flange 43, while 90 the lower portion of this flange 45 extends forwardly and downwardly in a straight line and terminates in spaced relation to the arcuate flange 46. A metallic reinforcing and wear plate 48 may be provided around 95 the upper extremity of the side bar of the minor section and the notch 41 is flared, as shown in Fig. 8, so that it may readily engage the arcuate flange 46. A wear plate 49 is secured upon the side bars 16 at an intermediate point of the length thereof, and this wear plate is constructed with spaced notches or slots 50 corresponding with slots or notches formed through the rib or flange 40 of the side bar. When the device is to be 100 used as a stair ladder, the minor section is slid upon the major section with the rib or flange 40 passing between and guided by the flange members 43 and 47 until the notches 50 are in alinement with the flange 46 and the extremity of the socket or angular flange 44, after which the minor section is moved pivotally so that the notches 50 will respectively engage the said flange 46 and the upper wall of the flange or socket 44, as 105 110 115 120 125 130

shown clearly in Fig. 9. The two sections will thus be effectually held together so that they will not separate while the ladder is in use and the latch 20 may, of course, be 5 swung into engagement with the minor section to further aid in holding them against separation. It will be readily noted that the flange 46 is engaged positively by the opposite walls of the lower notch 50 and the 10 upper wall of the socket 44 is likewise engaged by the opposite walls of the upper notch 50, while the sides of the flange or rib 40 rest against the lower wall of the socket 44, and the lower portion of the 15 flange 45, an ample support for any ordinary weight being thus provided.

In Fig. 12, we have shown a further embodiment of our invention in which the side bars 51 of the major ladder section have secured to their upper ends heads 52 which fit against the outer sides and the rear edges of the said side bars and project inwardly beyond the inner sides of said bars. At the rear edge of the side bar 51, the head 52 20 presents a straight flange 53 parallel with the side bar and a short outwardly and downwardly extending flange 54 at the lower end of said guiding flange 53. At the opposite edge of the side bar 51, the head 52 25 presents an upwardly flaring trough or channel 55 having a notch 56 in its rear edge and from the lower end of this channel a short guiding flange or lip 57 depends. The minor ladder section has its side bars 30 35 of rectangular cross section and the rungs 58 59 are secured to and extend between the same in any desired manner. When the device is to be used as a step ladder or a stair ladder, the minor section is merely slid 40 upon the major section to the desired degree, the side bars of the minor section being guided by the flanges 57 and 53, and, when the desired position has been reached, the minor section is rocked or swung pivot- 45 ally so that a rung 59 will enter the notch 56 and the opposite edges of the side bar 58 will bear against the base of the channel 55 and against the stop flange 54, as shown in Fig. 12 and as will be readily understood. 50 This arrangement provides for a very quick and easy adjustment of the minor section relative to the major section and is very cheap without losing any efficiency.

When a short straight ladder is desired, 55 either section of our device may be employed for that purpose, the sections being disconnected by merely swinging the minor section into position between the sides of the major section and then sliding it longitudinally of the major section so that it will clear the locking and sustaining flanges upon the major section. Inasmuch as the minor section will fit easily between the side bars of the major section, the device, when not in 60 use, may be stored in a small space and they 65

may be likewise nested when they are to be transported. While in the accompanying drawings we have shown in detail only one side of the ladder, it will, of course, be understood that all the described construction is duplicated at the two sides of the ladder and the locking and supportig means also constitute guiding means for holding the minor section in proper relation to the major section in the adjustment of the device. The anchoring or locking feet carried by the lower end of the minor section engage the major section in such a manner as to effectually prevent slipping of the minor section when the device is arranged as an extension ladder and the notches in the minor section engaging the flanges or rungs of the major section effectually prevent spreading of the device when it is arranged as a step ladder or as a stair ladder, while the latches pivoted upon the major section and arranged to engage the minor section will effectually prevent collapse of the device when set up for use as a step ladder or a stair ladder. The locking and guiding devices do not interfere with the separation of the sections when they are to be used separately nor do the locking or anchoring feet upon the minor section interfere with the adjustment of the same relative to the major section. The lower ends of the major section are so formed and constructed that a firm support for the device will be provided when it is used as a step ladder or a stair ladder without marring the surface upon which it may be set up while at the same time a gripping action may be had when the device is set up upon the ground for use as an extension ladder. Our device may be combined in any desired manner by any person without loss of time and with little labor and may be produced at a cost which is very materially below the cost of separate ladders capable of the various uses to which our device may be put. While we have shown and described several embodiments of the invention, it is to be understood that we do not limit ourselves to the exact construction disclosed, but various changes may be made therein without departing from the spirit or scope of the invention as the same is defined in the following claims.

Having thus described the invention, what is claimed as new is:

1. A ladder comprising a major section consisting of side bars and rungs extending between the side bars, a minor section consisting of side bars and rungs extending between the side bars, the minor section being adapted to fit between the side bars of the major section, locking feet pivotally mounted on a rung of the minor section and provided at their lower ends with means to engage a rung on the major section, a cross bar connecting the lock- 120 125 130

ing feet just below their pivotal mounting, resilient connections between the locking feet and the minor section holding the locking feet normally away from the major section, and means for limiting the pivotal movement of the locking feet in a direction away from the major section.

2. A ladder comprising a major section consisting of side bars and rungs extending between the side bars, a minor section consisting of side bars and rungs extending between the same, the minor section being adapted to fit between the side bars of the major section, locking feet pivotally mounted upon the lower end of the minor section, means on the minor section in constant engagement with the locking feet yieldably holding them away from the major section, stop plates carried by and depending from the lower ends of said locking feet, one of said plates being adapted to engage a rung of the major section, and stops on the minor section between the stop plates.

3. A ladder comprising a major section consisting of side bars and rungs extending between the side bars, a minor section adapted to fit between the side bars of the major section, locking feet pivotally mounted upon the lower end of the minor section, means on the minor section for limiting the pivotal movement of the locking feet away from the major section, yieldable means normally holding the locking feet in longitudinal alinement with the side bars of the minor section, and means on said locking feet to engage a rung of the major section.

4. A ladder comprising a major section, a minor section adapted to fit within the major section and slidably thereon, means for locking the minor section to the major section in a set position, the lower ends of the side bars of the major section each having an angularly disposed supporting face at one side, and an anchoring plate secured to the lower end of each of said side bars at the side thereof, opposite the supporting face, said anchoring plates being inoperative when the bars rest on said supporting faces.

5. A ladder comprising a major section, a minor section adapted to fit slidably within the major section, means for pivotally adjusting the minor section upon the major section, and means for holding the sections in a set position, the side bars of the major section consisting of three longitudinally extending members disposed in triangular relation, and brackets bridging the area between the said members and having angularly disposed portions secured to the members.

6. A ladder comprising side bars, thimbles inserted through said side bars and provided adjacent their inner ends with flanges to limit outward movement thereof and having their outer ends upset whereby to se-

cure the thimbles in the side bars, rungs having their ends fitted in the inner ends of said thimbles, and indentations in the inner ends of the thimbles embedded in said rungs.

7. A ladder comprising a major section, a minor section adapted to fit within the major section, means for permitting a limited pivotal movement of the minor section relative to the major section, and latches pivoted upon the major section and provided at their free ends with notches to engage the adjacent corners of the minor section whereby to prevent collapse of the sections and having forwardly projecting handles, said handles adapted to lie between the adjacent sides of the sections when in collapsed position and bear against the major section to limit the outward movement of the latches.

8. A ladder comprising a major section, a minor section adapted to fit within the major section, means for permitting a limited pivotal movement of the minor section relative to the major section, and latches consisting of flat plates pivoted at their lower ends upon the rear sides of the major section and having notches at their upper inner corners to engage the adjacent corners of the minor section and having forwardly projecting flat handle members at their inner edges adjacent said notches.

9. A ladder comprising a major section, heads secured to the upper end of the major section and provided on their inner sides with inwardly projecting flanges presenting straight parallel portions and angularly disposed stop portions, and a minor section having longitudinal ribs upon its sides adapted to slide between and be guided by the parallel portions of said flanges and having notches in said ribs adapted to engage the angularly disposed portions of the flanges upon pivotal movement of the minor sections whereby interlocking engagement between the sections will be effected.

10. A ladder consisting of a major section, heads secured to the upper end of said section and having lateral flanges on their inner faces, one of said flanges having a straight portion extending along the edge of the section, and an offset portion defining an angular socket projecting from the edge of the section at the end thereof, another flange having an end portion parallel with the straight portion of the first-mentioned flange and an obliquely disposed portion depending from said end portion parallel with a wall of the socket in the first-mentioned flange, and another flange defining an arc extending from a point below and in alinement with the oblique portion of the second-mentioned flange to a point below and spaced transversely of the section from the lower end of the first-

mentioned flange, and a minor section having longitudinal ribs on its outer sides adapted to slide between the parallel portions of the first and second-mentioned flanges, said ribs having notches therein whereby the minor section may be moved pivotally relative to the major section and effect engagement of the end of said section with the angular sockets of the first-mentioned flanges and engagement of the said notches with the last-mentioned flanges to prevent separation of the sections.

11. A ladder comprising a major section,

heads secured to the upper end of said section and having guiding portions parallel with the section and lateral angularly disposed channels and stops, the channels each having a notch in one wall, and a minor section slidable between said guiding portions and adapted to rock into engagement with the stops and channels with a rung resting in the notches in the channels.

In testimony whereof we affix our signatures.

EUGENE DARNELL. [L.S.]
LOUIS G. CASSIDY. [L.S.]
